UNITED STATES PATENT OFFICE.

WILLIAM E. HADLOCK, OF WENHAM, MASSACHUSETTS.

ELECTRIC ALARM-CLOCK.

SPECIFICATION forming part of Letters Patent No. 404,906, dated June 11, 1889.

Application filed February 8, 1888. Serial No. 263,416. (No model.)

To all whom it may concern:

Be it known that I, WILLIAM E. HADLOCK, of Wenham, county of Essex, State of Massachusetts, have invented an Improvement in Pilots' Clocks, of which the following description, in connection with the accompanying drawings, is a specification, like letters on the drawings representing like parts.

The object of my invention is to produce a clock for the use of pilots, the indications of which can be readily seen at night, as well as in the day-time, the said clock also being provided with means for giving a signal at the end of any desired period of time, and also with means for keeping a log or record of the course of the vessel.

The invention is embodied in a clock having a time-movement of any suitable or usual construction, the said movement being inclosed in an opaque case at the rear of a translucent dial, and at the rear of said case is a lantern by which the said dial may be illuminated when required, means being provided for sheltering the time-movement from the heat of the lamp, and also for quickly cutting off the light if required, so that there will be no local illumination to interfere with the observations of the pilot. The clock-case is also provided with an opening containing ground glass or other translucent material constituting a support for a recording strip or log, which may be held in place on said support by suitable clamps, said removable recording-strips being furnished with the names of the different stations or points that the vessel is to pass, and with suitable blanks opposite said points on which may be marked the time at which the vessel arrives at or passes each of the said points.

It is frequently necessary or desirable in steering the vessel to remain on a certain course for a definite period of time, and in order to prevent the necessity of continually watching or frequently observing the clock means are provided by which an alarm can be sounded at any desired moment, so that if, for instance, it should be desired to retain the vessel on a certain course for the period of five minutes, or if for any other reason the pilot needs to know just when the five minutes have elapsed, he can set the alarm device to sound a signal at the end of five min-

utes, and can then give his undivided attention to other things, instead of having to keep in mind a certain moment and to frequently observe the clock to know when the said moment arrives. The signal is produced by an electric alarm controlled by a circuit-closing device, a portion of which is carried by the hand of the clock and the other portion of which is movable by a suitable handle around the dial of the clock, so that it may be set any desired distance in advance of the clock-hand, which will close the circuit and cause the alarm to be sounded when it arrives at the member thus set.

In order to produce the minimum of resistance to the movement of the clock-hand, and at the same time insure the closing of the circuit and the retaining of the said circuit closed for a short interval only, the circuit-closer is of peculiar construction, and comprises a spring or yielding contact that completes the circuit when the hand arrives at the stationary member, and a second yielding contact, which is normally closed, but which is opened by the movement of the clock-hand with relation to the stationary contact before the first-mentioned contact or yielding circuit-closer has passed the stationary co-operating member and thus opened the circuit. By means of this device, which closes the circuit at one point and then opens it at another point, the circuit may be retained closed and the alarm caused to sound during any desired short period of time, while if the circuit were controlled wholly by the contact between the moving member carried by the minute-hand and the stationary member the closure would have to be of comparatively long duration.

Figure 1 is a front elevation of a pilot-house clock embodying this invention; Fig. 2, a side elevation thereof; Fig. 3, a central vertical section; Fig. 4, a front elevation of a portion of the hand and alarm-circuit closer carried thereby; Fig. 5, a side elevation of said circuit-closer; Fig. 6, a detail showing the several parts of the circuit-closer separately; and Figs. 7 to 9, inclusive, details to be referred to.

The chronometer or time-movement proper (indicated at *a*, Fig. 3) may be of any suitable or usual construction. The said clock-movement may be inclosed wholly or in part

in a suitable metallic case, preferably circular in shape, and itself supported by arms a' in the main clock-ease b , which may be of wood, and is provided with a dial c , of translucent material, so that the figures on said dial and a sufficient portion of the hands of the clock may be seen when the dial is illuminated from behind. The minute and hour hands $d e$ are carried by shafts or arbors projecting from the clock-movement a through the dial in the usual manner.

In order to illuminate the dial from behind, so that the time can be readily observed without external illumination, the case b has supported at its rear a lantern f , which is preferably fastened upon square tubes g , (see Fig. 7, which is a section on line x , Fig. 2,) one at either side of the clock-ease, so that said lantern is supported at some distance from the clock-ease.

The fastenings for the lantern are clearly shown in Figs. 3, 7, and 8, the latter being a rear view. The lantern f has lateral flanges f' , provided with small holes that fit over pins g' , projecting from the tubes g , and provided with notches that receive the ends of fastening-buttons f^2 , pivoted on the flange f' .

The rear side of the clock-ease is provided with an opening containing a pane of glass h , while the front of the lantern-ease f is also provided with a pane of glass h' , so that there are two separate panes of glass and an intermediate air-space between the lantern and the clock-movement, which is thus almost wholly protected from the heating effect of the lantern, as the air can flow up freely through the tubes g and through the space between the glass panes $h h'$.

In order to further intercept the light and heat when the illumination is not required or when for any reason it is desired to wholly cut off the artificial or local light, which might interfere with the pilot's observations, a flexible opaque screen i is provided, which is connected with a spring-roller i' , of any usual or suitable construction, and is provided with an operating-cord i^2 , carried over suitable pulleys or guides $i^3 i^4$, and provided with a handle i^5 , co-operating with a suitable catch or fastening i^6 outside the ease. (See Figs. 2 and 7.) Thus by drawing down the handle i^5 and placing it in the fastening i^6 , as shown in Fig. 2, the screen i is unwound from the roller i' and drawn up through the space between the panes of glass $h h'$, and wholly cuts the light of the lantern off from the dial; but by disengaging the handle i^5 the screen will immediately be wound on the roller i' , and thus permit the light to enter the clock-ease b and fall on the rear of the dial c , so that the time can be easily read. The lantern preferably has two or more burners, and the light is diffused in the ease and by the translucent dial, so that the clock-movement a does not obscure the dial.

One end of the clock-ease b is provided with a panel or opening b' , (see Fig. 2,) containing

ground glass or other translucent material, which affords a support for a tablet or log-strip k , which may have printed on it the 70 various stations or points of observation that the vessel is to pass, and from which the position of the vessel is known, and in connection with said station-names are spaces on which the time at which the vessel passes 75 such stations may be written by the pilot in charge, thus keeping a complete log or record of the run of the vessel. The ease b is provided with spring-clamps k^2 (see Figs. 2 and 9, the latter a section on line y , Fig. 2) at the 80 end of said tablet-support, by means of which the tablet may be held in place, and by which a new tablet can easily and quickly be substituted for one which is removed.

The light from the lantern f in the interior 85 of the clock-ease is sufficient to illuminate the paper tablets, so that the station-names can be easily read and the time indications properly made.

The hands $d e$ of the clock are covered by a 90 crystal m , supported in a bezel or annular frame composed of two parts $n n'$, the former containing the crystal m and screwing into the latter part n' , which is itself secured to the clock-ease b at the front of the dial. The 95 said crystal m is shown in this instance as bored in the center to form a bearing for a stud o , having a flange or collar o' , that rests against the inner surface of the crystal, and a milled head or handle o^2 , that fits over the 100 end of the stud and bears against the outer surface of the crystal, as clearly shown in Fig. 3, being preferably fastened upon the stud o by means of a screw o^3 , the stem of which screws into the stud o and the head of which bears 105 against the handle o^2 , so that the portions o o^2 may be drawn up against the face of the crystal as tightly as may be desired. A set-screw o^4 fastens the handle o^2 upon the stud o , so that it cannot turn independently, but 110 when turned will cause the stud to turn with it. The inner head or flange o' of said stud is provided with an arm or pointer p , the end of which bears with spring-pressure against a shoulder n^2 on the inner surface of the portion n of the bezel, thus making electric contact with said bezel in all positions of said pointer around the same. The said pointer is extended inward to the clock-dial and provided with a finger p' just over the minute-divisions, so that the said pointer may be accurately set at any desired position with relation to the minute-divisions. 115

The minute-hand d (see Figs. 4, 5, and 6) has supported on but insulated from it a 120 bracket r , having connected with it by a spring r' a carrier r^2 , of rigid material, having attached to its outer end a spring r^3 , provided at its end with a contact-finger r^4 , which in the normal condition of both springs $r' r^3$ 125 bears against a stationary contact-piece r^5 , supported on and electrically connected with the hand d of the clock, which is connected with one terminal 2 of the alarm-circuit, (see

Fig. 3,) the other terminal 3 of which is connected with the bezel $n\ n'$, and thus with the pointer p , which is provided with a contact projection p^2 . The contact-carrier r^2 has connected with it, near the end of the spring portion r' , a contact-spring r^6 , which in the advance of the hands will engage the contact p^2 and thus make electrical connection between the said point p^2 and the spring r^6 , carrier r^2 and spring r^3 to the contact r^5 on the hand, thus completing the alarm-circuit. As the hand advances, the spring r^6 remains in contact with the projection p^2 , preventing forward movement of the carrier r^2 , while the bracket r and contact r^5 continue to move forward with the hand. The spring r^3 will cause the contact r^4 to move forward with or follow the contact r^5 as it advances until the said spring brings up on the carrier r^2 , when the said spring r^3 and contact r^4 will also be arrested, owing to the engagement of the spring r^6 with the projection p^2 , and the contact r^5 in its further forward movement will break the circuit at $r^4\ r^5$, although the said circuit may be connected at $p^2\ r^6$ for some time longer. This construction permits a sufficient overlapping of the spring r^6 and projection p^2 to afford a certain contact without retaining the alarm-circuit closed for a long period, and all the springs are very delicate, so that the pressure does not retard the clock.

In turning the pointer p forward past the end of the hand the spring r^6 yields easily, so that the circuit-controlling device is not injured by the movement of the pointer past the end of the hand in either direction.

It is obvious that modifications may be made in the construction and arrangement of the parts without departing from the invention—as, for example, the main portion of the circuit closing and breaking device might be carried by the pointer p or its equivalent, instead of by the clock-hand, this being a mere inversion of the arrangement shown, and other changes will be readily suggested to persons familiar with the art to which the invention relates.

The pointer p is useful even as a visual indicator, and will be of assistance without the circuit-closer, or if the circuit were disconnected, so that the audible signal or alarm would not be operated.

The clock-movement supporting-arms a' are preferably connected with posts a^2 , that are connected with the bezel $n\ n'$, so that the clock-movement is retained accurately centered with the bezel, the said posts being com-

posed of or provided with insulating material, so as to prevent electrical connection between the clock-movement and bezel, except when the members of the circuit-closer connected, respectively, with said parts come into engagement.

When vessels are provided with incandescent electric lamps, one may be used in the lantern-case at the rear of the clock, in which case the heat-insulating arrangements $h\ h'$ may not be required.

I claim—

1. The combination of a clock-movement and hands thereof connected with an electric circuit, one of said hands being provided with an electric contact constituting one terminal of said circuit, with a crystal in front of said clock-hands provided with a circular metallic frame insulated from the clock-movement, but connected with and forming the other terminal of the before-mentioned electric circuit, and a pointer frictionally pivoted in said crystal concentrically with the clock-hands, the end of said pointer bearing with spring-pressure against the metallic frame of said crystal and being provided with a contact co-operating with the one carried by the clock-hand, substantially as and for the purpose described.

2. The combination of a clock-hand and electric contact fixed thereon with a yielding contact-carrier insulated from said clock-hand and provided with a spring-pressed contact normally engaging the said contact on the hand and a stationary contact co-operating with said yielding carrier, substantially as described.

3. An electric circuit closer and breaker for clocks, comprising two members, one carried by the clock-hand and the other located in the path thereof and completing the circuit when the member carried by the clock-hand engages the other member, combined with a contact-piece in the same circuit co-operating with one of said members, which is operated by the movement of the clock-hand, as described, whereby the circuit is broken, while the two members that originally closed it still remain in engagement, substantially as described.

In testimony whereof I have signed my name to this specification in the presence of two subscribing witnesses.

WILLIAM E. ILADLOCK.
